SECONDARY X-RAY DIAPHRAGM AND
METHOD OF MANUFACTURING THE
SAMECarl Niemann, Erlangen, Germany, assignor to
firm Siemens-Reiniger-Werke Aktiengesell-
schaft, Berlin, GermanyApplication June 6, 1936, Serial No. 83,952
In Germany June 8, 1935

3 Claims. (Cl. 250—34)

This invention relates to diaphragms for X-ray work and to methods of manufacturing the same, and refers more particularly to diaphragms used to intercept secondary X-rays.

Diaphragms for secondary X-rays used for medicinal purposes are usually placed between the patient and a photographic layer and consist of a large number of thin strips of an X-ray impervious material, such as lead, interconnected by a substance which transmits X-rays. Such diaphragms intercept secondary X-rays while transmitting primary X-rays to the photographic layer.

Practical experience has shown that it is extremely difficult to manufacture diaphragms of this type. The strips of X-ray impervious material are usually quite thin so that a single diaphragm may contain as many as one thousand of such strips. If all these strips are interconnected at one time, internal forces are apt to develop in them, causing a relative shifting of the strips. Obviously, such shifting is extremely undesirable, since when the diaphragm is finished, the shifted strips will produce a distorted X-ray picture, which may lead to incorrect diagnosis.

When the X-ray impervious strips are quite thin, for instance, when they have a thickness of a few tenths of a millimeter each, the manufacturing difficulties are increased still further. It is practically impossible, with methods known heretofore, to provide a diaphragm for secondary X-rays consisting of a large number of very thin ray-impervious strips which are directed toward the focal point of an X-ray tube situated at a predetermined distance from the diaphragm.

An object of the present invention is the provision of a diaphragm for secondary X-rays consisting of a large number of very thin X-ray impervious strips, all of which are situated in their proper relative positions.

Another object is the provision of a method of manufacturing diaphragms for secondary X-rays, by the use of which it is possible to obtain a diaphragm consisting of a very large number of very thin ray-impervious strips which are firmly and securely held in any desired respective positions.

The above and other objects of the present invention may be realized through the provision of a method of manufacturing diaphragms for secondary X-rays which comprises heating separately a ray-impervious strip (or a group of such strips), at least one of the surfaces of which was previously coated with a glue, such as adhesive wax or the like, which becomes soft when heated.

The heating is interrupted after the glue has

become soft. The softened layer of glue carried by the heated strip is maintained in contact with another strip and in the proper position relatively thereto, while the heated strip is allowed to cool. The layer of glue solidifies at the end of the cooling period and firmly connects the two strips. Then the same procedure is repeated with other strips until a diaphragm is formed consisting of the desired number of strips.

The heated strip may be maintained in its proper position relatively to another strip only during the cooling period, or it may be placed in that position sometime prior to the beginning of the cooling period.

Each of the ray impervious strips may consist of one sheet of X-ray impervious material, such as lead, or it may comprise two layers, one of which is impervious to X-rays, while the other one transmits X-rays.

The invention will appear more clearly from the following detailed description when taken in connection with the accompanying drawing, showing by way of example, preferred embodiments of the inventive idea.

In the drawing:—

Figure 1 illustrates diagrammatically a method of heating the ray-impervious strips by means of an exteriorly located coil;

Figure 2 is a diagram illustrating a method of heating the strips by means of a current passing through the strips.

Figure 3 shows a diaphragm consisting of a plurality of ray-impervious strips interconnected by layers of glue; and

Figure 4 shows a diaphragm each of the strips of which consists of a layer of X-ray impervious material and a layer of a material transmitting X-rays, such strips being interconnected by layers of glue.

Figure 1 of the drawing shows a strip 10 consisting of X-ray impervious material, such as lead. The strips 10 may have a length of about 400 mm., a thickness of about 0.4 mm. The glue 11 may have a thickness of about 0.1 mm., the strips may be about 2 mm. in breadth.

One side surface of the strip 10 is coated with a layer of glue 11. The glue should be of the type which becomes soft after having been heated to a certain temperature. For instance, adhesive wax may be used. The adhesive wax becomes soft after having been heated to a temperature of about 60 degrees (Celsius).

The strip 10 is held in the required position by a guiding device, such as a ruler 12. A suction device 13 is situated adjacent the ruler 12;

the device 13 is used to create air-suction, the force of which maintains the strip 10 in its proper position.

5 An elongated heating body such as an electrical wire 14 may be placed adjacent the strip 10. The heating wire 14 is supplied with an electrical current from a source of electrical energy 15.

10 The diaphragm is manufactured by placing a strip 10 having a layer of glue 11 upon the ruler 12 and maintaining it in the desired position by means of suction created by the suction device 13. Then the layer 11 of the strip 10 is heated by means of the heating wire 14 until the layer of 15 glue 11 becomes soft. Then the heating coil 14 is removed and another strip (not shown) is placed upon the heated layer 11 of the strip 10. Then the layer of glue 11 is allowed to solidify. The second strip may be pressed by hand against 20 the first strip, although the force of suction created by the device 13 is usually sufficient to maintain proper contact.

25 It is possible to use artificial cooling means, such as a nozzle 16 blowing cold air upon the heated layer 11 to shorten the cooling period which must be continued until the glue becomes hard and firmly connects the two strips.

Then a third strip is joined to the two interconnected strips by the same method.

30 The method is repeated until a diaphragm of the desired dimensions is completed.

Figure 2 of the drawing shows an X-ray impervious strip 10 coated with a layer of glue 11 and maintained in its proper position by means 35 of a ruler 12 and a suction device 13. The strip 10 and the glue 11 are heated by an electrical current passing through the strip and supplied to it by the terminals 17 and 18 connected through the time switch 19 with a source of electrical energy 15.

40 The terminals 17 and 18 may be so constructed that they contact that strip which has already been treated, and which is permanently connected by a hardened layer of glue with an adjacent strip. On the other hand, in the construction shown in Fig. 2, the terminals 17 and 18 are placed in contact with a strip which is to be connected with another strip (not shown) by means of layer 11.

50 The time switch 19 which may consist of any suitable relay, is used for closing the circuit supplying the electrical current to the terminals 17 and 18 for a predetermined period of time and then automatically interrupting this circuit so that the strip 10 is heated by the electrical current during a predetermined period of time. This period of time should be just sufficient to heat one strip 10 and its layer 11 to the desired extent.

60 A suitable variable resistance 20 may be included in this circuit for the purpose of adjusting the strength of the heating current.

65 The manufacturing process is substantially the same as the one already described. First, a strip 10 is coated by a layer of glue 11. The strip 10 is placed upon the ruler 12 and is maintained in its proper position upon that ruler by the suction device 13. Then the switch 19 is closed and an electrical current of predetermined strength is caused to flow through that strip for 70 a predetermined period of time. At the expi-

ration of this period the device 19 is automatically switched off, thus interrupting the circuit. Then a second strip (not shown) is placed over the first strip so that the softened layer of glue 11 contacts the adjacent surface of the unheated second strip.

Then the softened layer of glue is caused to solidify.

15 The blowing device 16 may be used to blow cold air upon the strips to cool the heated strip 10 quickly and thus shorten the period of time during which the layer of glue 11 solidifies. At the end of the cooling period the layer of glue has completely hardened and it firmly connects the two strips.

20 Then the same process is repeated with a third strip, a fourth strip and so on until the desired number of strips are assembled and a completed diaphragm is formed.

25 The manufactured diaphragms are illustrated in Figures 3 and 4 of the drawing. Figure 3 shows a diaphragm consisting of several ray-impervious strips 10 which are connected with each other by layers of glue 11. Figure 4 shows a diaphragm, each of the strips of which consists of two layers, viz., an X-ray impervious layer 10 and a layer 21 consisting of a material which transmits the X-rays. In this case also, all the strips are held together by layers of glue 11.

30 In the described methods the strips have been connected individually one to the other. In some instances it may be advisable to connect the strips in sets of several strips at one time, such sets consisting of several strips which have been connected one with the other in any suitable 35 manner.

What is claimed is:—

1. In a method of manufacturing diaphragms for secondary X-rays, the steps of coating at least one surface of a single strip which includes a layer of an X-ray impervious material with an adhesive substance, heating said strip until said adhesive substance becomes substantially soft, causing the softened adhesive substance to solidify, and maintaining said softened adhesive substance at least during the last-mentioned step in contact with a surface of another single strip which includes a layer of an X-ray impervious material, thereby firmly interconnecting said two strips in their proper relative positions. 50

2. In a method of manufacturing diaphragms for secondary X-rays, the steps of coating at least one side surface of a single X-ray impervious strip with an adhesive substance which becomes soft when heated, passing an electrical current through said strip to heat said strip and soften said adhesive substance, then cooling said strip and maintaining it at least during the cooling period in a predetermined position adjacent one other strip, said adhesive substance contacting the last-mentioned strip during the cooling period and firmly interconnecting said strips at the expiration of the cooling period. 55

3. A diaphragm for secondary X-rays, comprising a plurality of strips, each of said strips comprising a layer of substantially X-ray impervious material; and layers of adhesive wax interconnecting said strips and firmly holding said strips in their respective positions relatively to each other. 60
